by W. J. Johnston Attorney

UNITED STATES PATENT OFFICE.

PHILIP S. DUSENBURY, OF SEDALIA, MISSOURI, ASSIGNOR OF ONE-HALF
TO GEORGE A. MASTERS, OF SAME PLACE.

FILE HOLDER AND RACK.

SPECIFICATION forming part of Letters Patent No. 359,560, dated March 15, 1887.

Application filed August 2, 1886. Serial No. 209,814. (No model.)

To all whom it may concern:

Be it known that I, PHILIP S. DUSENBURY, a citizen of the United States, residing at Sedalia, in the county of Pettis and State of Missouri, have invented certain new and useful Improvements in File Holders and Racks; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.

My invention relates to an improvement in file holders and racks; and it consists in certain details of construction and operation, hereinafter more particularly described, and pointed out in the accompanying drawings, in which—

Figure 1 is a perspective view of my file holder and case. Fig. 2 is a vertical central section of same. Figs. 3 and 4 are details.

The object of my invention is the production of a cheap and simple file-case that may be easily and conveniently operated and readily closed and locked, and valuable papers and files thereby secured and preserved from interference by unauthorized persons, and from dust and injury.

My file-holder is composed of the parts A and B, joined at their ends in a position at right angles with each other, as shown in Fig. 1, and forming the front and bottom of the holder. Guide-rods F are inserted in the bottom piece, B, at each side near its outer end, and extend back parallel with piece A to a point near its outer end, where they are bent inward at right angles and their opposite ends inserted into and secured in piece A. These rods form a way or track for the follower G, which is provided with holes or openings at its sides, through which the rods pass, and enable the follower to slide upon them freely backward or forward. This follower consists of a block nearly corresponding in width and length to the piece B, as shown in Figs. 1 and 2.

The papers or files are placed between the guide-rods F, and between the follower and bottom piece, B, their ends resting upon piece A. In order to hold the follower G in any de-

sired position on the guide-rods F, I provide a tension device consisting of a pair of double-hooked plates, K K', the hooks of which rest upon the guide-rods F. These plates are placed in a reversed position in respect to each other, so that the hooks bear on opposite sides of the guide-rods. The plates are united or connected at their center by a looped spring, N, which forces them outwardly or apart, and causes the hooks of each to press firmly against the guide-rods. This tension device is secured to the outer face of the follower by a bolt, i, passing through the loop-spring and entering the follower, so that when the follower is pressed up against the papers the spring N causes the hooked plates to tightly grip the rod on opposite sides and hold the follower in position. It may be readily and easily loosened, when desired to move it backward or forward, by compressing the spring N with the thumb and finger.

The case or rack for the accommodation of my file-holders is provided with a raised track consisting of the rails O O, upon which the file-holder rests and slides. The inner sides of these rails are grooved to receive a plate, V, which fits and slides within said grooves. The movement of this plate is limited by a downward-projecting lug, e, at its rear end, which, in the backward movement of the plate, abuts against a stop, d, in the floor near the inner end of the track, and in its outward movement against a similar stop, d', near the outer end of the track. The front end of this plate is provided with two holes, a', and in the bottom of piece B of the holder is fitted a pair of hooks, H, designed to engage with these holes and connect the plate and file-holder, so that the backward or forward movement of the file-holder upon the track corresponds with that of the plate and enables the holder, when drawn out to the front of the case, to be dropped down to a horizontal position and suspended by means of the hooks H, as shown in Fig. 1.

Upon the bottom and inner end of piece B of the file-holder is secured a metallic plate, which projects slightly beyond its end, and is then turned up at right angles parallel with the end of said piece, to form the locking-hook M. (Shown in Figs. 1 and 2.)

Upon the inner side of the rear wall, C, of

the case is a locking-bolt, E, movably secured by screws or bolts *r*, passing through a series of diagonally-arranged guide-slots, *s*, whereby the said bolt is given a downward movement 5 when projected forward and an upward movement when drawn backward. This bolt E may be of any desired and suitable length, and is designed, when projected forward and downward, to engage with the hooks M of all the file-holders in the case. The outer end of this locking-bar is flanged or turned up, as shown in Fig. 1, and extends to a door opening into the side of the file rack or case, and may be connected therewith by a link, so that when 10 the door is opened the bar is withdrawn and the file-holders released or unlocked; or it may be withdrawn by hand. The operation of locking is, however, automatically performed by closing this door, which, in closing, bears 15 against the flange and presses the bolt inward. 20

The manner of operating my device is as follows: The side door is opened and the bolt withdrawn, unlocking and releasing all the file-holders. A file-holder is drawn outward 25 from the case until arrested by the lug on the under side of plate V coming in contact with the stop *d* near the outer end of the track. It is then permitted to drop forward and down, until its face A occupies a horizontal position 30 and its bottom piece, B, a vertical position, as shown in Fig. 1, and is held suspended by means of the hooks H, engaging with the holes *a'* in the front end of plate V. The follower G is then drawn back by placing the thumb 35 and finger upon the loop-spring N and compressing the same, which releases the tension of the hooks K K' upon the guide-rods F. The papers or files are then placed within the 40 holders in an upright position and securely clamped by pressing the follower forward against them. The holder is then raised to an upright position and pushed into the case until the face A is flush with its front, when the lug *e* on the under side of plate V comes in 45 contact with the rear-stop, *d*, and arrests its further backward movement, as shown in Fig. 2.

It will be observed that the hook M on the rear end of the piece A is now directly beneath the locking-bolt E. This bolt is now projected forward and carried downward within the hook M by means of the diagonal guide-slots *s*, and serves to securely lock the holder in position until the bolt is again withdrawn. 55

Near the top of piece A is provided an aperture extending from side to side, of sufficient width to insert a card, and in the front face of this piece is an opening, T, to this aperture for the purpose of displaying any label that may indicate the contents of the file-holder. 60

It is obvious that my file rack or case may be of any suitable dimensions to accommodate any desired number of file-holders, and that a single opening or door on the side may afford access to and operate the locking bolt 65

or bolts, so that all the file-holders may be closed and securely locked by means of a single key. 70

Having thus described my invention, what I claim, and desire to secure by Letters Patent, is—

1. In a file rack or case, the combination of the file-holder constructed as described, and having the attaching-hooks on the bottom, with the case provided with the track on the floor thereof, composed of the inwardly-grooved rails and the plate adapted to slide within said grooves, said plate being provided with 80 perforations at its outer end for attaching the holder by means of the hooks, substantially as and for the purpose set forth. 75

2. In a file rack or case, the combination of the inwardly-grooved rails on the floor of the 85 case, the plate adapted to slide within said grooves and provided with a downwardly-projecting lug at its inner end and perforations at its outer end, the studs or stops in the floor within and near each end of the track, 90 and the file-holder provided with hooks in its bottom for engaging with the holes in the front end of the plate, substantially as and for the purpose set forth.

3. The combination, in a file-holder, of the 95 front and bottom pieces, the follower having holes or openings at its sides, the guide-rods connecting the side and bottom pieces and passing through the openings in the follower, and the tension device secured to the follower 100 and consisting of the hooked plates united by a spring and bearing upon the guide-rods, substantially as described.

4. In a file-holder, the combination, with the follower mounted and moving upon guide-rods, of a tension device consisting of a pair of hooked plates occupying a position reverse to each other, so that the hooks grasp the guide-rods on opposite sides, said plates being connected by a looped spring forcing them 110 in opposite directions, substantially as and for the purpose described. 105

5. In a file rack or case, the combination, with the holder provided with a locking-hook secured to its lower and inner end, of a slotted locking-bolt having a flange at its outer end, said flange engaging with the inner edge of the case-door, whereby the locking device is automatically operated by the door and the holder thereby locked when the door is closed, 115 as set forth. 120

6. In a file-holder constructed as described, the face-piece A, provided with a recess from side to side, near its top, for the insertion of a card or label, and an opening in its face 125 communicating with said recess for displaying said label, substantially as and for the purpose described.

In testimony whereof I affix my signature in presence of two witnesses.

PHILIP S. DUSENBURY.
